The ornamental design for a wireless remote air conditioner thermostat, as shown and described.

DESCRIPTION

FIG. 1 is a front elevational view of the wireless remote air conditioner thermostat showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken line showing of an air conditioner and a receiver unit are for illustrative purposes only and forms no part of the claimed design.

*FIG. 1**FIG. 2**FIG. 3**FIG. 4**FIG. 5**FIG. 6*FIG. 7
